UNITED STATES PATENT OFFICE.

AMOS GETHING, OF ENTERPRISE, WEST VIRGINIA, ASSIGNOR OF ONE-THIRD TO JOHN P. WILLIS AND ONE-THIRD TO HOMER L. ICE, BOTH OF ENTERPRISE, WEST VIRGINIA.

RAILWAY-RAIL BOND.

No. 905,810.

Specification of Letters Patent.

Patented Dec. 1, 1908.

Application filed January 9, 1907. Serial No. 351,513.

To all whom it may concern:

Be it known that I, AMOS GETHING, a citizen of the United States, residing at Enterprise, in the county of Harrison, State 5 of West Virginia, have invented certain new and useful Improvements in Railway-Rail Bonds; and I do hereby declare the following to be a full, clear, and exact description of the invention, such as will enable others 0 skilled in the art to which it appertains to make and use the same.

This invention has relation to devices for bonding or uniting the joints of railway-rails of a track for the purpose of utilizing 5 the rails as a line of an electric circuit to conduct a power-current to operate signaling devices or any other means or things to which a power-current may be applicable in railway operations. 20 It is the object of the invention to provide a rail-bond that shall be first of all entirely efficient for the purposes for which it is intended, and that shall be simple in construction, and economic in manufacture, besides being ready and easy of application. 25

The nature of the invention is ascertainable from the device portrayed in the annexed drawings, forming a part of this specification, in view of which the invention will 30 first be described with respect to its construction and mode of use, and then be pointed out in the subjoined claim.

Of the said drawings—Figure 1 is a plan of the improved rail-bond. Fig. 2 is a side 35 elevation of the same. Fig. 3 is a side elevation showing the ends of two rails connected by my improved bond, with fish-plates in place over the bond. Fig. 4 is a horizontal sectional view of Fig. 3.

40 Similar numerals of reference designate similar parts or features, as the case may be, wherever they occur.

In the drawings 10 designates the intermediate portion of the bond which is preferably 45 flattened and is fitted against the sides of the web 11 of the rail and intermediate of the same and the fish-plate 12 that mechanically joins the ends of the rails.

13 designates the end portions of the bond 50 which are made round, the terminals 14 being bent at right angles to the plane of the body portion to adapt them to be driven tightly into holes made in the web for their reception so that a perfect electrical contact

shall be made between the rails and the 55 bond.

The end portions of the flattened part adjacent to the rounded end portions 13 are bowed outward, as at 15, for the purpose of taking up all vibrations and expansions and 60 contractions incident to their employment. The flattened parts between the rounded end portions and the bowed portions 15 are arranged to lie in the same plane as the intermediate flattened portion 10. The bowed 65 portions thus lie between two flattened portions in the same plane. The purpose of this is to bring a direct tensile and shearing stress on the terminals 14, these terminals thereby being prevented from subjection to 70 bending stresses.

In use the improved bond will have its intermediate flattened portion placed against the sides of the webs 11 of the end portions of two joining or abutting rails, and the 75 fish-plates 12 will be bolted to the rails as usual on the outside of the bond, which may be placed either above or below the bolts 16 which connect the fish-plates to the rails.

It is designed to make the bond of sufficient length that the ends of the fish-plate may not extend to the outward bow 15, so as not to interfere with the action of the said bow or bend in taking up vibrations and 80 accommodating itself to atmospheric influences. 85

The bond may be made of copper or any other good electrical conductor that is not easily liable to corrode, and that may possess other necessary properties. 90

What is claimed is—

A rail bond comprising a flat metallic bar adapted to be secured between the fish-plate and the rails to which the plate is connected, said bar comprising an intermediate portion, 95 end portions lying in the same plane as the intermediate portion and bowed portions lying between the end portions and the intermediate portion, and rounded extremities beyond said end portions bent at right angles 100 in a direction opposite to the projection of the bowed portions.

In testimony whereof, I affix my signature, in presence of two witnesses.

AMOS GETHING.
